ELECTROLYTIC PROTECTION OF METAL SURFACES

Bengt G. Brolinson, New York, N. Y.

Application August 1, 1940, Serial No. 349,124

1 Claim. (Cl. 204—196)

This invention relates to the electrolytic protection of metals and more particularly to a system and apparatus for the electrolytic protection of containers, such as heat exchangers, condensers or the like, in which there is limited space available for the insertion of electrodes.

In the electrolytic protection of metals for the prevention of corrosion, scaling, etc., it has been proposed to insert an anode in the liquid within the container and to connect the surfaces to be protected as the cathode to a source of current. In certain instances, however, it is inconvenient or impracticable to insert anodes in the containers themselves. Such is the case in certain types of heat exchangers or condensers wherein the space is not sufficient to receive the necessary anode surfaces. Furthermore, the cost of inserting anodes in a plurality of containers may be prohibitive.

In order to effect the necessary protection in cases of this kind it has been proposed to provide a separate anode chamber which is connected in the fluid circuit so that fluid passes through the anode chamber on its way to or from the container. The present invention relates particularly to this type of equipment and has for an object to provide a system of novel and improved construction, which is simple and convenient to install and which is efficient in operation.

Another object is to provide an anode chamber which is suited to protect a plurality of containers.

Another object is to provide an anode chamber having novel and improved details of construction and features of operation.

Another object is to provide a novel and improved anode support.

Still another object is to provide a novel and improved means for supplying current to an anode in an elongated anode chamber.

A further object is to provide an anode chamber which is so constructed and arranged that the sediment or accumulations therein, may be periodically removed so as to prevent clogging of the chamber or interruption of the operation of the system.

Various other objects and advantages will be apparent as the nature of the invention is more fully disclosed.

Although the novel features which are believed to be characteristic of this invention are pointed out more particularly in the claim appended hereto, the invention itself may be better understood by referring to the following description, taken

in connection with the accompanying drawings in which the specific embodiment thereof has been set forth with illustration.

In the drawings:

5 Fig. 1 is a top plan view of a bank of condensers having an anode chamber embodying the present invention associated therewith;

Fig. 2 is a side elevation thereof;

10 Fig. 3 is the vertical longitudinal section of the anode chamber taken along the line 3—3 of Fig. 2;

Fig. 4 is an enlarged detailed view of a portion of the anode chamber showing the anode support and the lead-in means for connecting 15 the anode to an external circuit;

Fig. 5 is a transverse section taken on the line 5—5 of Fig. 4;

Fig. 6 is a side elevation, partly in section, of an anode chamber containing a solid anode;

20 Fig. 7 is an enlarged section taken on the line 7—7 of Fig. 6 showing the construction of the current lead-in means;

Fig. 8 is a transverse section taken on the line 8—8 of Fig. 6 showing the anode support; and

25 Fig. 9 is a side elevation showing a bank of condensers with intermediate electrode chambers arranged for the serial flow of the fluid therein.

Referring to the drawings more in detail the invention is applied to a bank of containers, shown for convenience as condensers 10, which are connected by individual inlet pipes 12 having control valves 13 to an inlet header 11 to receive therefrom the fluid, which in the case of condensers may constitute cooling water. It is 30 to be understood that the condensers are also connected to a suitable outlet header, not shown.

The water is supplied from a main 14 to the inlet header 11 through a valve 15. An anode chamber 16 is positioned parallel to the header 40 11 and is connected at opposite ends to the ends of the header by elbows 17 and 18 controlled by valves 19 and 20 respectively, the arrangement being such that with the valve 15 closed and the valves 19 and 20 open the water is supplied from the main 14 through the anode chamber 16 and thence to the header 11 and the condensers 10. With the valves 19 and 20 closed and with the valve 15 open, water is supplied from the main 45 14 directly to the header 11 and thence to the condensers 10, the anode chamber 16 being then cut out of service and rendered inactive. It is to be understood that the condensers 10 may be of the tube and shell type or of any other standard construction having metal parts which are

50 subject to corrosion, scaling and fouling.

The anode chamber 16, as shown more in detail in Figs. 3 and 4, comprises a tube 21 having a cross section substantially greater than that of the main 14 and the header 11. The elbows 17 and 18 may be connected to the opposite ends of the tube 21 by means of flanges 23 and 24. The elbow 17 may be provided with a drain pipe 25 having a valve 26 therein which, when open, permits the sediment or other materials in the pipe 21 to be removed.

The anode chamber contains an anode which is shown as an anode tube 28, which may be closed if desired, mounted concentric with the tube 21 and insulated therefrom. The anode tube 28 may be supported by spaced pairs of legs 29, shown as insulators 30 (Figs. 3, 4 and 5) which may be attached to the anode tube by suitable means, shown as bolts 31. The outer surface of the anode tube 28 may be recessed to receive the insulators 30. The insulators 30 may be provided with caps 35 which may be formed with spherical surfaces, and may be provided with peripheral flanges 36 forming a cup in which the ends of the insulators 30 seat. The caps 35 may be provided with central pins 37, which may be threaded into tapped holes 38 in the ends of the insulators 30. Suitable gaskets 39 and 40 may be inserted over the ends of the insulator 30 to prevent injury thereto.

In order to position and secure the anode tube 28 a pair of positioning blocks 41 may be secured in the tube 21 in a position to be engaged by the legs 29. The blocks 41 may extend around a portion only of the periphery of the tube 21 so that the anode tube 28 may be inserted with the legs 30 out of alignment with the blocks 41. After insertion the tube 28 may be rotated to bring the legs 29 into locking engagement with said blocks 41 for positioning and securing the anode as shown.

For making electrical connection to the anode tube 28 an ear 45 may be secured thereto by suitable means such as by welding. A flexible connecting cable 46 may be secured to the ear 45 by a bolt 47.

The tube 21 may be provided with an opening 50 of sufficient size to afford access to the interior of the tube. The opening 50 may be closed by a cover plate 51 which may be secured by bolts 52 and may be provided with a sealing gasket 53. The cover plate 51 carries a lead-in assembly comprising a metallic sleeve 55 passing through the cover plate and secured therein by a flange 56 and a nut 57. An insulating sleeve 58 extends inwardly from the sleeve 55, and is secured with its opposite ends respectively in an annular recess 59 in the flange 56 and in an annular recess 60 in a connector block 61. A conducting rod 62 extends through the sleeves 55 and 58 and may be threaded into the block 61. Suitable insulation 63 such as mica may be provided around the rod 62 to insulate the same from the sleeve 55. The assembly may be secured by means of lock nuts 64. An insulating gasket 65 may be inserted over the sleeve 55 to insulate the lock nuts 64 and the rod 62 therefrom.

The flexible connecting cable 46 may be provided with a flat connector 70 secured by means of a nut 68, to a threaded shank 69 formed on the block 61. The exposed parts of the cable 46, the block 61 and the ear 45 may be wrapped with insulation so as to completely seal the conducting parts from contact with the water in the tube 21.

The tubes 21 and 28 may be provided with holes 74 and 75, respectively, in registration with the legs 29 to permit inspection or adjustment thereof if desired, without dismantling the entire apparatus. The holes 74 may be closed by covers 76 secured by bolts 77.

For flushing out the anode chamber 20 and removing deposits from the anode a set of nozzles 80, controlled by individual valves 82, is provided. 10 In the embodiment shown these nozzles 80 are arranged in groups of three peripherally spaced about the tube 21 near the ends of the anode tube 28 and directed towards the center of said tube. The aligned nozzles 80 at the two ends 15 of the tube 21 may be connected to pipes 84 which are in turn connected to pipes 83 which are connected to a high pressure header 84 controlled by a valve 85 so that water under pressure may be supplied to said nozzles when desired. The 20 nozzles must be arranged to provide a maximum clearance from the anode and may, if desired, be mounted in chambers raised above the surface of the tubes 21 similar to the chamber formed by the T 111a to be described, or the nozzles may 25 be made of non-metallic material.

In the operation of this device the valve 15, Fig. 1, is normally closed, and the water is supplied to the condenser 10 through the anode chamber 16. It is to be noted that the condensers 30 are connected to the header 11 in parallel and that the anode chamber 16 is connected in series with the bank of condensers. Suitable electrical connections are made to the surfaces to be protected and to the rod 62 supplying current to the 35 anode 28, so that the anode is made positive and the surfaces to be protected are made negative. The anode itself, however, corrodes and must be renewed or replaced periodically.

It has been found that after the system has 40 been operated for a substantial length of time the anode chamber 16 becomes clogged due to the particles deposited from the anode and from the water itself and due to the scale which is removed from the anode. The chamber may be periodically cut out of service for cleaning by opening the valve 15 and closing the valves 19 and 20. The chamber may then be flushed out by opening the valves 85 and 82 and supplying water to the nozzles 80. The material thus removed from the anode falls to the bottom of the anode chamber and may be flushed out of the drain pipe 25. If sufficient water is not received from the sprays 80 for this purpose the valve 20 may be opened to supply water to the chamber to flush out the 55 accumulated material. The system may also be reserve-flushed by opening the valve 19 and closing the valve 20 to supply water through the elbow 17 to the anode chamber.

When the anode 28 is to be removed the cover 60 51 may be removed to afford access to the cable 46 which may then be disconnected. The elbow 17 may then be removed and the anode may be withdrawn axially. It is to be noted, however, that the anode must first be rotated to release the 65 supporting legs 29 from the blocks 41. The cover plates 70 76 may be removed for purpose of inspection or repair of the blocks 41. The flushing out of the anode chamber and the inspection provided for by the various inspection ports permits the anode to be maintained in continuous service without dismantling except when it is necessary to remove and renew the same.

In certain instances it may be desirable to use 75 a solid anode such as a solid carbon or graphite rod. This embodiment of the invention is shown

in Figs. 6, 7 and 8 wherein the anode chamber 16 is similar to that above described. An anode rod 90 is provided, however, which in this embodiment is supported by legs 91 of suitable insulating material having secured therein, threaded studs 92 which are also secured in suitable tapped holes 93 in the anode rod 90. Suitable recesses 94 are provided in the anode rod to receive the ends of the legs 91. The legs 91 are provided with caps 95, similar to the caps 35 above described.

In this embodiment the lead-in means differs from that shown in Figs. 1 to 5. As shown in detail in Fig. 7 the lead-in means comprises an insert 96 of impervious material such as treated graphite which may be threaded into a tapped recess in the side of the anode rod 90. A washer 97 may be positioned beneath the insert 96 to facilitate assembly and removal thereof. A terminal stud 98 is threaded into the insert 96 and an insulating sleeve 99 is threaded over the stud 98. The end of an insulated, flexible conductor 100 is inserted in a recess in the pin 98 and may be secured by a set screw 101.

In order to make a water-tight seal so as to prevent moisture from entering beneath the ends of the insulation of the conductor 100 a packing box is formed by the insulating sleeve 99 which is closed by means of a non-metallic gland 102, threaded in said sleeve. The sleeve 99 may be seated on a sealing gasket 103.

The other end of the conductor 100 is connected to a rigid lead-in comprising a metal sleeve 110 which passes through a cover 111 mounted on a T 111a and secured by bolts 111b. The T 111a provides clearance to obtain the length of insulator surface required to prevent surface creepage. The sleeve 110 may be secured in the cover 111 by nuts 112 and 113. A gasket 114 and a washer 115 may be provided to effect a water-tight seal. An insulating sleeve 116 extends inwardly from the sleeve 110 and is secured by a current conducting rod 117 which extends through the sleeve 110 and 116. A coating of insulating material 118, such as mica, surrounds the rod 117 to insulate the same from the sleeve 110. The sleeve 116 is clamped between a threaded head 124 and the sleeve 110 by means of a nut 120 threaded on the rod 117. Sealing gaskets 121 and 122 may be inserted over the ends of the sleeve 116 and an insulating washer 123 may be disposed between the sleeve 110 and the nut 120.

A terminal stud 119 may be threaded onto the end of the rod 117. The end of the conductor 100 is secured in the terminal stud 119 by means of a set screw 126. A packing box is formed by an insulating sleeve 127 which is threaded onto the stud 119, and a non-metallic gland 128. An insulating and sealing gasket 125 may be inserted between the head 124 and the sleeve 127. All electrical conducting members are thus sealed from contact with the water within the tube 21. The flexibility of the conductor 100 permits expansion of the parts due to temperature changes without damaging the equipment.

The embodiment shown in Figs. 6, 7 and 8 provides for the use of a solid anode rod. This may be desirable in the case of graphite or carbon rods, which have the property of protecting the cathodic surfaces without discoloring the liquid or introducing any metal ions therein.

In the embodiment shown in Fig. 9 a plurality of containers 130 are connected for the serial flow of water therethrough and a plurality of anode chambers 131 are arranged intermediate

the condensers. The water flows in series through the containers and through the intermediate anode chambers. For example, the first anode chamber 131 may be supplied by water from a line 132. Water is supplied from the first anode chamber 131 through a supply line 133 to the first container 130, and is discharged from the first container through a discharge line 134 leading to the second anode chamber 131. Similar connections are made to the remaining containers and anode chambers.

In this system the anode chambers are positioned adjacent the inlet to each container so as to obtain the most efficient action. The anode chambers are shown as graduated in size according to the temperature of the fluid in the various containers so as to take advantage of the increased conductivity of the hotter fluid, by reason of which less anode surface may be required. It is to be understood that the anode chambers 131 are similar in construction to the anode chambers 16 above mentioned and may be bypassed when desired, consequently the details thereof have not been repeated.

In the system shown in Fig. 1, a single anode chamber is used to protect the plurality of condensers. In the system shown in Fig. 9, a plurality of anode chambers are used, one for each condenser or other element to be protected. The particular system used will depend upon the requirements of each individual case and may differ according to the metals present, the nature and content of the cooling fluid and the conditions of operation.

Since the anode chamber is filled with water or other conducting fluid, it is essential to completely insulate all conducting members. It is also necessary to provide sufficient flexibility to permit relative movement between the anode and the anode chamber due to expansion or contraction of the parts. In the embodiment of Figs. 1 to 5 this is accomplished by connecting a flexible cable between the anode and an insulated lead-in which passes through the wall of the anode chamber. In the embodiment shown in Fig. 8, connection is made by means of a flexible insulated conductor. The joints between the conductor and the two terminal studs 98 and 119, however, are completely insulated and sealed by the stuffing boxes so as to prevent water from creeping inside the insulating covering. This construction prevents the conducting members from corroding due to contact with the water.

It is to be noted that the lead-in of Fig. 4 may be completely assembled and tested in the factory. This eliminates the necessity for assembling and testing the conductors in the field. Furthermore, the cable 46 may be disconnected by the removal of the nut 68 without disassembling the lead-in itself. This is an important feature from a commercial standpoint inasmuch as it is more difficult to obtain a permanent water-tight assembly in field than in a factory where there are proper facilities for assembling and testing.

The invention has been described as applied to the electrolytic protection of condensers as an example. It is to be understood, however, that the system may be applied to any group of containers, such as heat exchangers, boilers, feed water heaters, tanks or the like where such protection is required.

Although a specific embodiment of the invention has been shown for purposes of illustration, it is to be understood that various changes

and modifications may be made therein as will be readily apparent to a person skilled in the art. The invention is only to be limited in accordance with the following claim.

What is claimed is:

A device for the electrolytic protection of metal surfaces in a container, comprising an anode chamber, an anode in said chamber, and lead-in means extending through said wall to make an electrical connection with said anode, said lead-in means comprising a metallic sleeve extending through said wall and secured thereto, an insulating sleeve extending inwardly from said first sleeve, a lead-in rod extending through said sleeves, insulating means surrounding said

lead-in rod to insulate the same from said metallic sleeve, a terminal block carried by said lead-in rod, means on said rod to clamp said sleeves against said block, a terminal block

5 mounted in said anode, said terminal blocks having bores to receive the ends of a connecting cable, a flexible cable connected to both of said terminal blocks, said cable having an insulated covering, the ends of which are inserted in said 10 bores and stuffing boxes associated with the bores of each of said terminal blocks to seal the ends of said insulation from the surrounding medium and prevent contact thereof with said cable.

BENGT G. BROLINSON.
